Primary Examiner — Patricia A Palasik(57) **CLAIM**

The ornamental design for a robot as shown and described.

DESCRIPTION

FIG. 1 is a front elevational view of a robot showing our new design, showing the robot with the cabin closed;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a top, front and right side perspective view thereof;

FIG. 8 is a top, rear and right side perspective view thereof;

FIG. 9 is a front elevational view of the robot, showing the robot with the cabin open;

FIG. 10 is a rear elevational view of FIG. 9;

FIG. 11 is a right side view of FIG. 9;

FIG. 12 is a left side view of FIG. 9;

FIG. 13 is a top plan view of FIG. 9;

FIG. 14 is a bottom plan view of FIG. 9;

FIG. 15 is a top, front and right side perspective view of FIG. 9; and,

FIG. 16 is a top, rear and right side perspective view of FIG. 9.
